(No Model.)

C. W. WEISS.
EXPLOSIVE ENGINE.

No. 543,165.

Patented July 23, 1895.

UNITED STATES PATENT OFFICE.

CARL W. WEISS, OF BROOKLYN, ASSIGNOR TO HIMSELF, AND AUGUST MIETZ, OF NEW YORK, N. Y.

EXPLOSIVE ENGINE.

SPECIFICATION forming part of Letters Patent No. 543,165, dated July 23, 1895.

Application filed October 19, 1894. Serial No. 526,345. (No model.)

To all whom it may concern:

Be it known that I, CARL W. WEISS, of Brooklyn, in the county of Kings and State of New York, have invented certain new and useful Improvements in Explosive Engines; and I do hereby declare that the following is a full and exact description thereof, reference being had to the accompanying drawings, and to the letters of reference marked thereon, 10 making a part of this specification.

This invention relates particularly to explosive engines in which the charge is compressed in the motor-cylinder before ignition takes place.

15 One object is to increase the efficiency of explosive engines of the well-known Otto type, in which the cycle of actions is completed during two revolutions of the crank-shaft, the end particularly in view being to provide 20 means whereby in engines of this particular type it may become possible to take advantage of the establishment of an elastic cushion against the front side of the piston, which shall be compressed during the forward movement 25 of the piston and shall be made to do work by expansion during the return stroke of the piston. Incidentally to the successful development of this portion of the invention and as a result of the peculiar conditions 30 which obtain it has been found both desirable and necessary to provide certain special means for lubricating the piston, which means are also applicable to single-acting engines.

The several features of the invention will 35 be more particularly described hereinafter.

In the accompanying drawings, Figure 1 is a partial longitudinal section of so much of an engine of the Otto type as will be sufficient to enable the application of the present 40 improvements to be understood. Fig. 2 is a partial transverse section on the line $x-x$ of Fig. 1. Fig. 3 is a partial longitudinal section through a cylinder equipped with means different from those shown in Fig. 1 for effecting a displacement and cooling of the air or gas which forms the cushion against the front side of the piston.

The supporting-framework A may be of any suitable construction, and, as represented 50 in Fig. 1, has a bearing B for the crank-shaft

F, a slideway D for the cross-head E, and receives and supports the cylinder C. Within the cylinder is placed the piston G, having a piston-rod g, which is connected by the rod g' with the crank-shaft F. The rear end of 55 the cylinder is closed as usual by a head C' and the front end is also closed by a head C², so that either in the front end of the cylinder or in connection therewith there may be formed a tight chamber, within which the 60 inclosed gas or air may be compressed by the forward stroke of the piston to give up to the piston on its return stroke the energy so stored up. As represented in the drawings, the cylinder is surrounded by a jacket C³, which 65 forms between itself and the cylinder an annular space having free communication with the forward end of the cylinder. The space thus formed might be given any capacity by enlarging the jacket; but I prefer the arrangement 70 shown, in which the rear end of the space between the cylinder and jacket is connected through a check-valve H, which opens from the cylinder to a pipe C⁴, the space between the jacket and cylinder being relatively small as 75 compared with the volume of the cylinder. The pipe C⁴ is given a suitable length by coiling and is connected to the forward end of the space between the cylinder and jacket through a check-valve H' which opens inward. 80 The capacity of the chamber thus formed is still further increased by the connection to the pipe C⁴ of a tank I, which also serves another purpose to be referred to. Assuming for a moment that the engine is single acting, 85 it will be seen that the air or gas contained in the inclosed space and chamber is compressed during the forward stroke of the piston, and such increase of temperature as may be due to compression is utilized to maintain 90 the heat of the cylinder at a time when it is desirable to have it so maintained. The air or gas is at the same time forced through the valve H into the pipe C⁴, where its temperature is lowered materially. As the piston begins 95 its return stroke, the compressed and cooled gases from the pipe C⁴ re-enter the cylinder near its forward end through the valve H' and impart the stored-up energy to the piston. As the gases re-enter the hot cylinder 100

they are heated and their expansion increased, thereby adding still more to the work accomplished.

It will be apparent that the arrangement described constitutes means for displacing, cooling, and returning to the proper point for most effective action on the returning piston the gases which have been compressed by the forward movement of the piston.

10 It is assumed above that the engine is single acting, and so far as the operation of the devices already described is concerned they are applicable alike to single-acting engines and to those of the particular type to which reference has been made. It is well known, however, that in engines of the Otto type the explosion takes place during the first forward movement of the piston, the dead gases are expelled during the first rearward movement, the 15 fresh charge is drawn in by the second forward movement, and the fresh charge is compressed during the second rearward movement. It is undesirable that the pressure of the compressed gases should rest upon the front face 20 of the piston during the drawing in of the fresh charge, as the engine would then be doing negative work. Moreover, it is more desirable that the pressure should rest upon the front face of the piston during the compression 25 of the fresh charge than during the expulsion of the dead gases. I have therefore provided means for cutting off communication between the main body of the compressed gases and the space in front of the piston immediately upon the completion of the first 30 forward movement of the piston and re-establishing such communication upon the beginning of the second return stroke. Accordingly I have interposed a slide valve K between the valve H' and the jacket C³, the 35 said slide-valve having a port k, which is adapted to establish communication from the valve H' to the space within the jacket C³. The slide-valve is operated from the crank-shaft F by suitable mechanism, it being shown as connected by a rod K' with a crank-pin f on a disk f'. The latter is carried by a short shaft f², (shown in dotted lines,) which has a gear f³ engaged by a pinion f⁴ of half the number 40 of teeth on the shaft F. As the shaft f² rotates once for every two rotations of the shaft F, it is evident that the slide-valve K will be caused to open communication from the valve H' during the stroke of the piston which 45 compresses the fresh charge. The valve remains in the same condition during the next outward stroke of the piston under the influence of the explosion, whereby the gases in the enclosed space are compressed within the tank 50 I, the valve H opening outwardly to permit this. The valve K is then shifted as the crank of the shaft F passes through its dead-center and shuts off communication between the valve H' and the forward end of the cylinder. The valve K remains in this condition during the stroke of the piston which 55 expels the dead gases and the stroke which

draws in the fresh charge and then changes to the position first described. In this manner the gases within the chamber represented by the pipe C⁴ and the tank I are compressed by the explosion of the charge and return their stored-up energy to the piston during the compression of a fresh charge, while during the expulsion of the dead gases and the drawing in of the fresh charge the pressure on the front side of the piston is relieved and negative work avoided. As the volume of the annular space between the cylinder and jacket is relatively small as compared with the volume of the cylinder the pressure in such space and on the front side of the piston will be reduced below the atmospheric pressure by the first inward stroke and restored by the second outward stroke. In this way the movement of the piston is somewhat cushioned, although an exhaust-port might be opened to establish communication with the outer air.

A further improvement which has been incidental to the development of the main part of the invention relates to the means for lubricating the piston. The difficulty of providing means to apply a lubricant constantly to the pistons of engines of this type without causing leakage is well known. I have taken advantage of the compression of the gases in front of the piston to produce the feed of the lubricant. The tank I is adapted to receive a quantity of lubricant and is entered by a pipe i, which terminates below the level of the lubricant in the tank. The pipe i is connected with an extension i', which has two check-valves i² and i³, both opening upwardly and terminates in an opening i⁴ through the wall of the cylinder at such a point that the mouth of the opening i⁴ is touched or covered by the piston at the end of its forward stroke. As the air and gases in front of the piston are compressed in the manner already set forth, the pressure is transmitted to the surface of the lubricant in the tank I and, owing to the slight compression of the mingled gases and lubricant in the pipe i' between the two check-valves, a small quantity of lubricant is forced through the check-valve i³. In this manner the pipe i' between the two check-valves is filled with lubricant more or less mingled with gases. It is evident, therefore, that when the pressure is released the gases and lubricant between the two check-valves will expand slightly and a small quantity of lubricant will pass through the upper check-valve i². The lubricant is thus fed slowly to the opening i⁴ in the wall of the cylinder and is received upon the piston. The slide-valve K, heretofore referred to, may be interposed between the pipes i and i' and be provided with a port k⁴ to prevent the forcing out of the lubricant from the tank I by the pressure of the compressed gases on its surface at a time when the exhaust-port in the front end of the cylinder is opened.

I have hereinbefore described an arrange-

ment of means for displacing, cooling, and returning to the cylinder at the proper point the gases compressed by the forward stroke of the piston. In Fig. 3 I have represented 5 a different arrangement for accomplishing this result. The cylinder C, its jacket C³, and the head C², closing the front end of the jacket, may be as usual. The jacket C³ instead of communicating with a pipe C⁴, in 10 which the compressed gases may be cooled, has around its forward end a water-jacket C⁵, the water-jacket being limited to a comparatively-narrow belt at the forward end of the cylinder, in order that its cooling influence 15 may be exerted only at that end of the cylinder. Within the space between the cylinder C and the jacket C³ is placed a loosely-fitting sleeve C⁶, which is adapted to be pushed to and fro by rods C⁷ C⁷, which pass through 20 the head C². The sleeve C⁶ being about half the length of the cylinder C and fitting loosely will displace the gases within the inclosed space as it is moved to and fro. The sleeve does not move with the piston but lags behind it. Consequently when the piston is at 25 the end of its outward stroke the sleeve is near the rear end of the cylinder and the compressed gases consequently remain for a brief time in proximity to the water-jacket C⁵. 30 As the piston commences its return movement the sleeve moves to its forward position and therefore displaces the gases toward the rear end of the space, where they are heated by contact with the hot portion of the cylinder 35 and are consequently expanded, thereby increasing the pressure upon the front side of the piston during its return stroke.

I claim as my invention—

1. In an explosive engine, the combination 40 with the cylinder, of a jacket surrounding the cylinder with a space between which communicates with the forward end of the cylinder, the forward end of the cylinder and said space being tightly closed so that the contained gas or gases shall be compressed by the forward movement of the piston to expand and do work upon the piston as it makes its return movement, means to displace the air or gases in said space as the engine is operated, and a cooling device, whereby the air or gas is cooled as it is compressed during the forward stroke of the piston and is returned to contact with the heated cylinder for further expansion by increase of temperature as

the piston makes its return stroke, substantially as shown and described. 55

2. In an explosive engine, the combination with the cylinder, of a jacket surrounding the cylinder with a space between which communicates with the forward end of the cylinder, the forward end of the cylinder and said space being tightly closed, a pipe having its ends respectively connected to the space inclosed by the jacket near the respective ends of the cylinder, a check-valve opening away 60 from the jacketed space in the pipe near the rear end of the cylinder and a check-valve opening toward the jacketed space near the forward end of the cylinder, substantially as shown and described. 70

3. In an explosive engine, the combination with the cylinder having its forward end tightly closed, of a chamber communicating with the forward end of the cylinder, a valve controlling the communication between the chamber and forward end of the cylinder, and means for operating said valve at successive movements of the piston, whereby communication is open to permit compression and subsequent expansion of the inclosed gases during certain movements of the piston and whereby said communication is closed during other movements of the piston to hold the gases inclosed in the chamber under compression and to relieve the front of the piston of their pressure, substantially as shown and described. 80

4. In an engine, the combination with the cylinder having its end closed to permit of compression of the inclosed air or gases by 90 the piston, of a closed chamber communicating with the cylinder and adapted to receive a lubricant, a pipe entering said chamber with its end below the surface of the lubricant therein and having its other end communicating with an opening into said cylinder, and two check-valves in said pipe separated by some distance from each other and both opening from said chamber, substantially as shown and described. 95

In testimony whereof I have signed my name to this specification in the presence of two subscribing witnesses.
